TIME DELAY SWITCH

Alick Clarkson, Bloomingdale Township, Du Page County, Ill., assignor to Vapor Car Heating Company, Inc., Chicago, Ill., a corporation of New York

Application November 29, 1939, Serial No. 306,637

8 Claims. (Cl. 200—97)

This invention relates to a new and improved time-delay switch for closing either single or multiple contacts after a lapse of a predetermined time period and in which the said multiple contacts may be closed either simultaneously or in sequence at predetermined time intervals.

The improved switch closes automatically in response to electrically energized means and is so designed that it closes with a regulated rate of movement throughout its entire travel. It is opened automatically, at a substantially faster rate, by spring pressure when the said closing means is de-energized and may also be opened by mechanical means, for example, a fluid pressure device, while the said electrical closing means remains energized. However, when the influence of said mechanical opening means is removed, while the electrically energized closing means is effective, the switch will again move to its closing position with the impeded rate of movement above mentioned.

While the present switch construction may be used, as above indicated, in various situations, the improvements have special utility, because of their novel cooperation with the other elements, when embodied in a fluid pressure control switch of the type shown in my copending application Serial No. 242,708, filed November 28, 1938. Specifically the present invention has been designed as an improvement on the switch structure shown in the said copending application and, therefore, will be described herein as constructed and used for the same purpose, that is to say—a multiple contact starter switch for the motor of a steam generating plant, for example, the blower motor of a fluid-fuel burner.

The switch comprises a unitary carriage on which is supported a plurality of separate contact fingers. It is moved to its closed position by the reflex or contraction force of a spring which is tensioned by means which are electrically energized whenever a main switch in a main control circuit is closed. In order to insure the closing of the contacts in sequence at uniform time intervals the contraction of the switch closing spring is impeded, preferably by a dash-pot device constructed to accurately control the rate of the contracting movement of the said spring, there being provisions made for compensating for the gradually reduced force of the spring tension as the switch approaches its closed position. When the main control circuit is opened the starter switch will be automatically opened by means of a spring which was put under compression during the closing

movement of the switch. The said fluid-pressure means for opening the switch to stop the motor may be set to be effective whenever a predetermined maximum fluid-pressure is exceeded. This member of the switch assembly can be set 5 to maintain any desired steam pressure within certain limits, for example, 150 pounds per square inch. When the motor starter switch has been opened automatically by the rise of pressure above the predetermined limit in the steam 10 generator, the switch, upon a sudden fall of pressure in the steam generator below the predetermined limit, will close slowly so that the several contact fingers will be brought into circuit closing position at uniform time intervals. 15

The principal object of this invention is to provide an improved time delay switch in which the closing operation of the switch may be accurately controlled and thereby maintain a uniform rate of movement throughout its entire 20 closing operation.

Another and more specific object is to provide an improved automatically controlled starter switch of the type briefly described hereinabove and disclosed more in detail in the specifications 25 which follow.

Other objects and advantages of this invention will be more apparent from the following detailed description of one approved form of switch assembly constructed and operating according 30 to the principles of this invention.

In the accompanying drawings:

Fig. 1 is a vertical section taken through a pressure controlled delay switch assembly and illustrating the improved construction of the 35 present invention.

Fig. 2 is a fragmentary view in front elevation of the upper portion of the assembly, showing the pressure setting and indicating mechanism.

Fig. 3 is a fragmentary sectional view similar 40 to Fig. 1 but illustrating the starter switch in its open position.

Fig. 4 is a front elevational view of the starter switch showing the relative positions of the several contact fingers.

Fig. 5 is a sectional plan view taken on line 45 5—5 of Fig. 1, and

Fig. 6 is a wiring diagram.

The improved switch comprises a carriage or frame 10 pivotally supported intermediate its 50 ends on a fulcrum pin 11 which extends through a pair of ear members 12 formed on or suitably secured to a base plate 13. An insulating block 14 is suitably secured to one end portion of the pivoted carriage. This insulating block is pref- 55

erably formed with a plurality of grooves 15 in which are positioned the several contact fingers 16, 17, 18, 19 and 20 (Fig. 4). One end of each contact finger is pivotally attached to the block 5 by a pin 21 of insulating material. The other end of each contact finger is preferably yieldably supported between pairs of coil springs 22 and 23 which are seated in pockets formed in the block 14 and in the insulating cross-bar 24 associated therewith. Adjustable contact members, one for each contact finger, are designated 16a, 17a, 18a, 19a and 20a and are adapted to be accurately positioned with relation to the fixed contact members, hereinafter described, with 15 which the said adjustable contacts are engaged when the switch is moved to its closed position. Obviously, the said contacts may be so positioned as to make simultaneous contact with the said cooperating fixed contact or they may be positioned out of horizontal alignment with each other, as shown in Fig. 4, so that they will move successively into engagement with the fixed contacts at suitably spaced intervals. In the present disclosure the end portions of the contact fingers 20 are preferably bent out of horizontal alignment, as indicated in Fig. 4, so that the operation will require less flexing of the contact fingers when they are positioned to move into successive contact with the fixed contacts above referred to.

25 The timing of the intervals between the closing of the contacts of the several fingers is determined by the spaced offset relation of the movable contacts together with the speed of the switch closing movement.

30 The fixed contacts are designated 26, 27, 28, 29 and 30 (see Fig. 4). The said contacts 26 and 27 are supported on a metallic bracket 31 mounted on an insulating block 32 which in turn is suitably secured to the base 13 of the switch 40 assembly. The other fixed contacts 28, 29 and 30 are supported on a similar metallic bracket 33 which is secured to the said insulating block 32. The purpose of the above grouping of the fixed contacts on the separate brackets 31 and 45 33 will appear more clearly hereinafter from the description of the several circuits of the wiring diagram shown in Fig. 6. Each of the fixed contacts 26 to 30, inclusive, when the switch is used in a situation which requires a snap opening and 50 closing action, is positioned between the upwardly extending legs of a horse-shoe shaped permanent magnet 34. It will be apparent from this disclosure that when the switch carriage 10 is rocked about its pivotal axis in a switch closing direction, the contact finger 16 will be first to move into the operating range of its permanent magnet 34, whereupon this arm will be suddenly drawn downwardly (compressing spring 22) so as to engage the pair of switch contacts 16a and 26. 55 If the said switch is moved at a uniform rate of speed throughout its full closing range the contacts 17a, 18a, 19a and 20a will be brought, successively, into engagement with the fixed contacts 27, 28, 29 and 30, respectively, at uniformly spaced time intervals, each movable contact being snapped downwardly by its magnet 34.

The mechanism for automatically closing the switch comprises a solenoid coil 35 which is housed in a casing 36 suspended from the bottom face of the base plate 13 (Fig. 1). The coil is centered about a vertical guide tube 37 having a core plug 38 fitted in its upper end and secured to the upper wall of the casing 36. A movable core 39 is guided within the lower portion of the guide tube 37 and through a collar

40 secured to the lower wall of the casing 36. The upper end, preferably, of a tension spring 41 is secured to the lower end of the movable core 39 and the lower end of said spring is secured to a centrally disposed tubular extension 42 formed on a dash-pot piston 43. A push rod 44 is also secured to the upper end of said cylindrical extension 42, preferably by means of a pin 45 and extends upwardly through central bores 46 and 47 formed in the movable core 39 and the core plug 38, respectively. The upper end of the push rod 44 is operatively connected with the operating arm 10a of the switch carriage. This operative connection may be of any approved construction which makes adequate provision 14 for the change in the angular position of the operating lever of the switch carriage during the closing and opening movements of the switch. For the purpose of the present illustration, a block 48 is secured to the upper end of the push 20 rod 44. An upstanding web 49 on the block is formed with an open slot which receives a cross pin 49a fitted in the clevis end of the switch operating arm 10a.

From the construction thus far described it 24 will be apparent that when the starter switches are opened, as shown in Fig. 3, the movable core 39, the dash pot plunger 43, and the push rod 44 will be in their lowermost position relative to the bottom of the dash pot cylinder 50. It will 30 also be apparent that in such position of the parts mentioned the movable core 39 will rest on the spring 41 and the said spring will be free of tension. By the closing of the main control switch I (see Fig. 6), the solenoid 35 will be energized and the movable core 39 will be drawn upwardly thus tensioning the spring 41 which in turn exerts resilient lifting pressure on the push rod 44 and thereby tilts the switch carriage 10 in a direction to close the several contacts thereof. Naturally the movable core 39 will be drawn upwardly the full extent of its travel substantially instantaneously with the closing of the main control switch I. Therefore, inasmuch as the push rod 44 is lifted solely by the tension 46 force or contraction of the spring 41, any variation in the voltage of the main control circuit will not affect the rate of the switch closing movement. The upward movement of the rod 44 relative to the core 39 is limited by a stop collar 51 44a which is adjustably fixed on the rod 44.

The rate of the switch closing movement is controlled entirely by controlling the rate of contraction of the spring 41. This result is accomplished in the present invention by the bypassing of the fluid 51 contained in the dash-pot 56 around the dash-pot piston 43 in progressively increasing volume as the piston is drawn upwardly by the tension of the spring 41.

The proportionate increase in the volume of fluid by-passed to a position below the dash-pot piston compensates for the proportionate reduction in the tension force of the spring 41 and thereby insures the closing of the several contacts 16a to 20a, inclusive, at uniformly spaced intervals. For the purpose of illustrating one approved means for impeding the contraction of spring 41 so as to obtain the results above mentioned, the inner wall 52 of the dash-pot cylinder 50 is tapered slightly so that a proportionately larger amount of the fluid 51 will pass between the dash-pot piston and the cylinder wall, as the said piston is drawn upwardly. In order to provide for adjustably varying the switch-closing time period the dash-pot piston is provided 71

with a plurality of small leak holes 53 of different sizes, one or more of which may be opened by adjusting the position of a disc valve 54 so that a slot 55 in the valve will uncover the feed hole or holes desired. The said disc valve is held in position by a spring 55a interposed between the valve and the pin 45. A ball 56 positioned in the cylindrical extension 42 of the dash-pot piston operates to close a central port 57 during the upward movement of the dash pot piston, but is unseated by the pressure of the fluid 51 during the downward movement of said piston so as to permit free passage of fluid therethrough and thereby permit a relatively fast switch opening movement.

When the solenoid coil 35 is deenergized, the switch carriage 10 is tilted in a clockwise direction to the switch-opening position shown in Fig. 3 by means of a coil spring 58 positioned beneath the contact end of the switch carriage so as to be compressed by the closing movement thereof. The said spring 58 is somewhat lighter than the switch-closing spring 41 and is supported on a vertically adjustable seat 59.

In addition to the spring 58 for opening the switch when the control circuit through the solenoid 35 is broken, the switch mechanism is illustrated herein in connection with a pressure actuated device adapted to open the switch, without disturbing the energization of the solenoid 35, when the pressure in the steam generating plant rises above a predetermined pressure. This pressure actuated means comprises an upper casing 59, secured to and suspended from the base 13, and a lower casing 60 between which a flexible diaphragm 61 is clamped. A pipe 62 leading from the source of fluid under pressure, for example, steam, is threaded into the nipple 63 of the lower casing 60 and communicates through passage 64 with a pressure chamber 65 beneath the diaphragm 61. A plunger 66 seats on the upper face of the diaphragm 61 and extends upwardly to a point beneath the switch carriage 10. The upper end of the plunger is normally out of contact with the said switch but is adapted to press upwardly on a ball 67 secured in a suitable pocket formed on the switch carriage body to open the switch when the steam pressure in the pressure chamber 65 rises above a predetermined pressure. The fluid pressure required to lift the plunger 66 and thereby open the switch 10 is determined by the amount of compression imparted to spring 68, 69 which are confined between upper and lower head members 70-71. The lower ends of the said springs 68-69 rest on the lower head which in turn is normally supported on the casing 59, but is engaged by shoulders 70 formed on the lower end of the plunger 66 when the plunger is lifted or forced upwardly by the pressure in chamber 65. A movable sleeve rack 71 is movably fitted on the upper end portion of the switch opening plunger and seats in a self centering bearing 72 formed in the upper spring head 70. Compression is imparted to the said springs 68-69 to correspond to a maximum selected pressure for the pressure chamber 65 by adjusting the sleeve rack 71 vertically. This adjustment is effected by means of a pinion 73 mounted in the casing 59 to engage the teeth of the sleeve rack 71. The pinion shaft extends out of the casing 59 and carries at its outer end a suitable hand wheel 75 whereby the pinion 73 may be rotated to raise and lower the sleeve rack 71 and thereby vary the compression of the spring 68, 69. The pinion 73 is held in any desired adjusted

position by means of clutch mechanism 76 (Fig. 2). This clutch mechanism is not illustrated specifically in this application since its specific construction does not affect the operation of the improvements disclosed herein, it being understood that any suitable form of mechanism for locking the shaft 74 against accidental rotation may be used. Preferably, a pointer 77 is operatively secured to the shaft 74 so as to indicate the pressure at which the mechanism is set to open the switch 10.

Assuming now that the switch 10 is in its closed position, indicated in Fig. 1, and the solenoid 35 is energized: When the fluid pressure in chamber 65 rises above a selected maximum, for example 150 pounds per square inch, the switch opening plunger 66 will be forced upwardly against the compression of spring 68-69 to open the switch 10. The opening movement of the switch forces the switch closing plunger rod 44 and dash pot 20 plunger 43 downwardly. Inasmuch as the solenoid 35 remains energized the movable core 39 remains in its upward position. Consequently the downward movement of the push rod 44 and dash pot 43 imparts tension to the spring 41 whereby, 25 in the event that the pressure in chamber 65 is suddenly lowered or reduced, the switch 10 will be again closed automatically by the contraction of the spring 41 and this closing movement will be retarded by the action of the dash pot piston, 30 as previously described, to effect the uniform switch closing movement. However, if the control circuit through the solenoid 35 should be broken while the switch is held open by the pressure operated plunger 66, the spring 58 will support the switch in its opened position when the plunger 66 is lowered as a result of the fall of pressure in the chamber 65. It will be also apparent from the above description that if the main control switch I should be opened and 40 subsequently closed while the pressure actuated plunger 66 is in its raised position, the movable core 39 of the solenoid will move to its up position and thereby put the spring 41 under tension so that it will be effective to close the switch 10 45 as soon as the steam pressure in the chamber 65 is reduced below the maximum for which the pressure device is set.

The several conduit wires connected to the individual switch contacts, it will be understood, 50 are connected with suitable terminals in a box N shown at the left of Fig. 1.

Referring now to Fig. 6 which illustrates a simplified wiring diagram for the switch. At A is indicated a source of electric power for energizing a motor B (for example, the blower motor for fluid-fuel burner) said motor having a shunt field C. At D, E, F, G and H are indicated a plurality of similar relays. The switch contacts of relays D to G, inclusive, are respectively 60 opened when the relays are deenergized. The switch contacts of the relay H are normally closed when the relay is deenergized, but is opened when the relay is energized. With the main control switch I open, as shown in Fig. 6, 65 the motor B is at rest, the electro-magnet 35 is de-energized, the movable core 39 of the electro-magnet 35 is in its lowermost position and the switch closing spring 41 is free of tension, and all of the starter switches are open. Assuming now that control switch I is moved to the completely closed position, the movable switch contact 78 will engage the two fixed contacts 79 and 80, and movable contact 90 will engage the fixed contact 91. The electro-magnetic device 75

35 will now be energized through the following circuit: From battery A through wire 92, switch contacts 90 and 91, wire 93, solenoid 35 and wire 94 back to the battery. The energization of the 5 solenoid 35 results in drawing the movable core 39 upwardly for its full travel, thereby tensioning the switch closing spring 41 to impart closing pressure to the switch 10 with the uniform time controlled movement previously described. The 10 movable contact 16a will first engage fixed contact 26, thus completing a circuit energizing relay D as follows: from battery A through wire 92, switch contacts 78 and 79, wire 95, starter switch contacts 26 and 16a, wire 96, relay D and wires 15 97 and 98, back to the battery. The switch contacts of relay D will now be closed, thus completing a circuit through the armature of the motor B as follows: from battery A through wire 99, motor B, wire 100, resistances J, K and L, wire 20 101, contacts of relay D and wires 102 and 98 back to the battery. At the same time a shunt circuit through the motor field will be completed as follows: from the wire 99, through field C, wires 103 and 104, closed contacts of relay H and 25 wires 105 and 106 to wire 101 and thence as before, back to the battery.

Shortly thereafter the second pair of starter switch contacts 17a and 27 will be engaged thus 30 energizing relay E through a circuit similar to that previously described for relay D. This will short-circuit resistance L through wire 107 and the closed contacts of relay E. In a similar manner, the successive energization of relays 35 F and G will successively cut out the resistances K and J, thus successively building up the current in the motor armature circuit. When the last pair of starter switch contacts 20a and 30 are closed, the last relay H will be energized so as to open the relay switch contacts and break 40 the shunt circuit through wires 103 and 105 around a resistance M so that this resistance will now be thrown into series with the field C of the motor so as to increase the motor speed. It will thus be seen that the simple act of closing 45 the single control switch I will cause electromagnetic device 35, through the resulting tension imparted to the spring 41, to effect a closing of the several starter switches in properly timed relation so as to preferably build up the 50 current and speed of the motor B. If switch I is opened, magnet 35 will be de-energized, whereby the spring 58 will then function to open all of the starter switches to stop the motor.

Assuming now that the switch I remains closed 55 and the electro-magnetic device 35 remains energized, if the steam or other fluid pressure in the system builds up above the predetermined desired maximum, the pressure-operated plunger 60 will function in a manner already described to open the starter switches and thereby stop the motor.

It is sometimes desirable to operate the motor B for a short period at a reduced speed, for 65 example, while warming up the system preliminary to the normal operation. In order to do this, the switch I is moved to an intermediate position so as to engage contact 18 with fixed contact 79 but not to engage the fixed contact 80. The first pair of relays D and E will now 70 be successively energized to start the motor and then cut out resistance L, but the motor will then be permitted to run with the resistances K and J in the armature circuit, and without the resistance M in the field circuit. The closing 75 of the remaining starter switches will be inef-

fective to energize the relays F, G and H since the circuits for these relays are open at the contact 80. After the system is warmed up, the control switch I is preferably opened to break all circuits by the opening of the starter switch 5 momentarily, whereupon the closing of the main control switch will then be effective to re-energize the electro-magnet 35, whereby the starter switches will be closed successively at uniform time intervals in the manner first described. 10

I claim:

1. In combination with a switch, means for automatically closing the switch comprising an electro-magnetically operated device in a control circuit and operable for its full movement 15 immediately upon the closing of the control circuit and a coil spring operatively engaging the switch and said electro-magnetically operated device, whereby the said spring is stretched by the operation of said device and thereby exerts 20 closing pressure on the switch, a dash-pot for retarding the contraction of the spring to prolong the closing movement of the switch and including means for compensating for the gradually reduced force of the spring during said 25 contraction, whereby the closing movement of the switch is maintained at a substantially uniform rate throughout its full travel, and a second spring positioned to be compressed by the closing movement of the switch for opening the 30 switch when said control circuit is broken.

2. In combination with a switch, means for automatically closing the switch comprising an electro-magnetically operated device in a control circuit and operable for its full movement 35 immediately upon the closing of the control circuit and a coil spring operatively engaging the switch and said electro-magnetically operated device, whereby the said spring is stretched by the operation of said device and thereby exerts 40 closing pressure on the switch, means for retarding the contraction of said spring comprising a dash-pot having a fluid by-pass around the piston which increases in area in proportion to the contraction of the spring and a consequent 45 reduction in force exerted thereby, whereby the switch-closing movement is maintained at a uniform rate of speed for the full travel of the switch.

3. In combination with a switch, means for 50 automatically closing the switch comprising an electro-magnetically operated device in a control circuit and operable for its full movement immediately upon the closing of the control circuit and a coil spring operatively engaging the switch and 55 said electro-magnetically operated device, whereby the said spring is stretched by the operation of said device and thereby exerts closing pressure on the switch, means for retarding the contraction of the spring comprising a dash-pot having 60 a fluid by-pass around the piston which increases in area in proportion to the contraction of the spring and the consequent reduction in force exerted thereby, whereby the switch-closing movement is maintained at a uniform rate of speed 65 for the full travel of the switch, and means for adjustably varying the retarding action of the dash-pot.

4. In combination, a switch comprising a plurality of fixed contacts and a plurality of cooperating movable contacts, a carriage on which said movable contacts are so mounted as to engage successively with the respective fixed contacts, a spring for moving the carriage in a switch closing direction, an electrically operated device 70 75

in a control circuit and adapted upon the closing of said control circuit to make said spring effective for closing the switch, means for controlling the rate of movement of the carriage in a switch closing direction, whereby the several contacts are closed successively at uniformly spaced intervals, and a pressure operated device operable at a predetermined pressure for swinging the said carriage in a switch-opening direction in opposition to the switch-closing spring and for repositioning the said means for controlling the rate of movement of the carriage.

5. In combination, a switch comprising a plurality of fixed contacts and a plurality of movable contacts, a unitary pivoted carriage on which the movable contacts are mounted to engage successively the fixed contacts, means for automatically moving the said carriage in the switch-closing direction comprising an electro-magnetically operated device in a control circuit and operable for its full movement immediately upon the closing of said circuit, a coil spring operatively connecting the switch carriage and the electro-magnetically operated device, whereby said spring is tensioned by the operation of the electro-magnetic device to impart switch-closing movement to said carriage, means for controlling the rate of contraction of said spring, a pressure operated device operable at a predetermined selected pressure for moving said carriage in a switch-opening direction while the said control circuit remains closed, and means for automatically moving said carriage in a switch-opening direction when said control circuit is broken.

35. 6. In combination, a switch comprising a plurality of fixed contacts and a plurality of movable contacts, a unitary pivoted carriage on which the movable contacts are mounted to engage successively the fixed contacts, means for automatically moving the said carriage in the switch-closing direction comprising an electro-magnetically operated device in a control circuit and operable for its full movement immediately upon the closing of said circuit, a push rod engaging 40 the switch carriage, a coil spring operatively engaging said push rod and the electro-magnetically operated device, whereby said spring is tensioned by the operation of the electro-magnetic device to lift the push rod and thereby impart 45 switch-closing movement to said carriage, means for controlling the rate of contraction of said spring, a pressure operated device operable at a predetermined selected pressure for moving said carriage in a switch-opening direction while the 50 said control circuit remains closed, and means for automatically moving said carriage in a switch-

opening direction when said control circuit is broken.

7. In combination, a switch comprising a plurality of fixed contacts and a plurality of movable contacts, a unitary pivoted carriage on which the movable contacts are mounted to engage successively the fixed contacts, means for automatically moving the said carriage in the switch-closing direction comprising an electro-magnetically operated device in a control circuit and 5 operable for its full movement immediately upon the closing of said circuit, a push rod engaging the said switch carriage, a coil spring operatively engaging said push rod and the electro-magnetically operated device, whereby said spring is tensioned by the operation of the electro-magnetic device to lift the push rod and thereby impart 10 switch-closing movement to said carriage, means for controlling the rate of contraction of said spring comprising a dash-pot having a fluid bypass which increases in area in proportion to the contraction of the spring and including means for adjustably varying the time period of the switch-closing operation, a pressure operated device operable at a predetermined selected pressure 15 for moving said carriage in a switch-opening direction while the said control circuit remains closed, and for repositioning the dash-pot piston for the control of a subsequent switch closing operation, and means for automatically moving 20 said carriage in a switch-opening direction when said control circuit is broken.

8. In combination, a switch comprising a plurality of movable contacts, a plurality of fixed contacts, a carriage on which the movable contacts are so mounted as to engage successively with the respective fixed contacts, a spring for moving the carriage in its switch-closing direction, an electrically operated device in a control circuit and adapted upon the closing of said control circuit to make said spring effective for closing the switch, means for controlling the rate of movement of the carriage in its switch closing direction, whereby the several contacts are closed successively at uniformly spaced intervals, 35 and a pressure operated device operable at a predetermined pressure for swinging the carriage in a switch-opening direction in opposition to the switch-closing spring, and for repositioning the said means for controlling the rate of movement 40 of the carriage, whereby said controlling means is made effective for controlling the rate of a subsequent closing movement of the switch whenever the pressure in the pressure operated device is suddenly reduced below a selected maximum. 45

ALICK CLARKSON.
